UNITED STATES PATENT OFFICE.

OSCAR M. SHECK, OF CLEVELAND, OHIO, ASSIGNOR TO THE ARGUS LAMP AND APPLIANCE COMPANY, OF CLEVELAND, OHIO.

ADJUSTABLE LAMP-SOCKET.

1,285,427.

Specification of Letters Patent. Patented Nov. 19, 1918.

Application filed July 7, 1917. Serial No. 179,274.

To all whom it may concern:

Be it known that I, OSCAR M. SHECK, a citizen of the United States, residing at Cleveland, in the county of Cuyahoga and State of Ohio, have invented certain new and useful Improvements in Adjustable Lamp-Sockets, of which the following is a specification.

This invention relates to the supporting means or socket for electric lamps. In certain types of electric lamps wherein a filament is employed the best illuminating results for certain purposes are obtained by having the filament occupy a particular position relative to the object to be illuminated. This is particularly desirable where the certain type of lamp is used in connection with motion picture apparatus, or for stage lighting.

20 In the construction of the lamps there exists irregularity in the position of the filament relative to the threaded base of the lamp. While in some lamps when the base is in contact or operative position in the ordinary socket the filament is in the desired relative position, others differ so that the proper adjustment cannot be made in the threaded socket.

The object of the present invention is the provision of adjustable means whereby the lamp may be given a partial turn, more or less, in the socket to bring the filament to the desired position and the operative contact retained.

35 With this object in view the invention consists in the construction, arrangement, and combination of the elements hereinafter described and pointed out definitely in the claims, reference being had to the accompanying drawing forming a part of the specification and in which similar characters of reference designate similar parts.

In the said drawing Figure 1 is a central vertical section of the improved socket and adjusting means, showing a lamp in contact position.

Fig. 2 is an underside view, and Fig. 3 is a cross section on line 3—3, Fig. 1.

In the illustrations the improvement is shown as applied to a lamp socket attached to a certain type of support, and while it is particularly adaptable to this embodiment it will be understood that the invention is not confined to this type of contact block or

socket support, as the following description 55 will disclose.

Referring now to the several figures of the drawing, 1 represents a socket supporting block made of suitable insulating material. 2 is a screw socket similar to the ordinary screw socket adaptable to accommodate the threaded base 3 of the lamp 4.

The socket 2 is attached to the insulated block 1 by suitable means such as screws 5, and one electric contact member 6 is connected with said socket as shown at 2^a. The electric circuit is closed by the lamp member 3^a contacting the metallic disk 7 which is connected with the electric contact member 8 by the member 7^a. The principles of construction thus far described are substantially old in the art, therefore the patentable novelty lies in the construction of the other elements and their co-operative combination with the said parts above set forth.

75 Threaded through the block 1 is a tubular plug 9 having a web 9^a therein forming two recesses 9^b and 9^c. A stem 10, preferably provided with an attaching flange 10^a is soldered, riveted or otherwise firmly attached to the disk 7. The stem 10 extends through an aperture 9^d in the web 9^a and is upset to form a retaining head 10^b. Mounted on the stem 10 within the recess 9^b is a spiral spring 11 one terminal of which 80 bears on the flange 10^a, or on the disk 7 the other terminal bearing on the web 9^a. The lower terminal of the plug 9 is provided with a slot 9^e to accommodate a suitable tool 85 such as a screw-driver, for the purpose of turning said plug in its threaded connection with the block 1.

90 The operation of the device is evident from the foregoing description of the construction and arrangement of the several elements. The raising and lowering of the plug member 9 through its threaded connection with the block 1, co-acting with the spring 11 provides a resilient adjustment of the contact disk 7, so that the lamp 4 may be 100 adjusted to the desired position in the socket 2 and the contact of members 3^a and 7 maintained.

105 It will be understood that the salient feature of the invention or the combination of adjusting elements is applicable to socket supports of various designs, and not confined to the specific support shown.

What I claim and desire to secure by Letters Patent is.

1. In a lamp socket, the combination of a base member; a socket member attached to said base member; contact plates attached to the exterior of the base member, one of said plates connected with the socket member; a resilient contact member attached to the opposite plate and extending into the socket; a stem on said resilient contact member; a hollow plug threaded through the base, the stem of the contact member extending into said hollow plug and having a resilient connection with said plug whereby threaded movement of the plug in the base will impart yielding adjustment to the interior contact member.

2. In an adjustable lamp socket the com-

bination of a base; a socket member adapted to receive the base member of an electric lamp, said socket member being attached to the first named base; a contact member within said socket; a stem attached to said contact member; a plug member having a recess therein, threaded through the base; a web in said plug provided with an aperture, the aforesaid stem passing through said aperture and having a head on its outer terminal; and a spring in the recess, said spring bearing on the contact member and on the web in the plug.

In testimony whereof I affix my signature.

OSCAR M. SHECK.

Witness:

FRANK R. BLAKESLEE.
